US0D1099080S

(12) **United States Design Patent** (10) **Patent No.:** **US D1,099,080 S**
(45) **Date of Patent:** **** Oct. 21, 2025**

(54) **LOUDSPEAKER**

(71) Applicant: **Genelec Oy**, Iisalmi (FI)

(72) Inventors: **Jussi Väisänen**, Iisalmi (FI); **Stephen Millar**, Iisalmi (FI); **Harri Koskinen**, Helsinki (FI); **Pietu Borén**, Iisalmi (FI)

(73) Assignee: **Genelec Oy**, Iisalmi (FI)

(**) Term: **15 Years**

(21) Appl. No.: **29/916,572**

(22) Filed: **Nov. 14, 2023**

(30) **Foreign Application Priority Data**

May 15, 2023 (EM) 015021553-0001

(51) **LOC (15) Cl.** **14-01**

(52) **U.S. Cl.**

USPC **D14/215**

(58) **Field of Classification Search**

USPC ..... D14/125, 155, 160, 168, 170–172, 188, D14/204, 209.1, 210, 213–216, 219, 222, D14/240, 300, 356, 358, 363, 509 CPC ... H04R 9/06; H04R 5/02; H04R 1/02; H04R 1/026; H04R 1/345; H04R 1/2834; H04R 1/2888; H04R 1/288; H04R 1/2819; H04R 2400/07; H04R 2400/11; H04R 3/12
